(57) **CLAIM**

The ornamental design for a ceiling fan motor housing, as shown and described.

DESCRIPTION

FIG. 1 is a top perspective view of a ceiling fan motor housing showing our new design in the environment of a ceiling fan;

FIG. 2 is an enlarged top perspective detail view of the ceiling fan motor housing, showing the portion encircled in FIG. 1;

FIG. 3 is an enlarged top perspective view of the ceiling fan motor husing shown in the environment of a ceiling fan;

FIG. 4 is a bottom perspective view of the ceiling fan motor housing shown in the environment of a ceiling fan;

FIG. 5 is a top plan view of the ceiling fan motor housing;

FIG. 6 is a top perspective view of the ceiling fan motor housing; and,

FIG. 7 is a side elevational view of the ceiling fan motor housing.

Portions of the ceiling fan motor housing shown in dash-dash broken lines form no part of the claimed design. The dash-dot-dot-dash lines form no part of the claimed design and only designate the border of an enlarged view.

1 Claim, 7 Drawing Sheets
